UNITED STATES PATENT OFFICE.

ELMER L. POWL, OF LANCASTER, PENNSYLVANIA.

RECEPTACLE-FILLING MACHINE.

1,371,435.

Specification of Letters Patent.

Patented Mar. 15, 1921.

Application filed July 11, 1917. Serial No. 179,941.

To all whom it may concern:

Be it known that I, ELMER L. POWL, a citizen of the United States, residing at R. F. D. #1, Lancaster, in the county of 5 Lancaster and State of Pennsylvania, have invented a new and useful Receptacle-Filling Machine, of which the following is a specification.

The subject of this invention is a receptacle filling machine intended primarily for filling receptacles with liquid, and wherein vertically reciprocating valves for controlling the supply of liquid are cooperatively associated with horizontally moving 15 can conveyors, and the objects of the invention are, first, to provide a can filling machine which will deliver fixed quantities of liquid to a can, second, to provide adjustable means for regulating the quantity of liquid 20 to be delivered to each can, third, to provide an intermittent motion for delivering and removing the receptacles, fourth, to provide a machine which may be easily disassembled and cleaned, fifth, to provide a simple and 25 efficient can filling machine.

With the foregoing and other objects in view, which will appear as the description proceeds, the invention resides in the combination and arrangement of parts and in 30 the details of construction hereinafter described and claimed, it being understood that changes in the precise embodiment of my invention herein disclosed can be made within the scope of what is claimed, without 35 departing from the spirit of the invention.

One practical embodiment of the invention is shown in the accompanying drawings, wherein:—

Figure 1 is a front elevation of the machine showing the front door open and the tank sectioned on the line 1—1 of Fig. 3, and the conveyer removed.

Fig. 2 is a side elevation of the machine; a part of the conveyer broken away.

Fig. 3 is a top plan view with a part of the conveyer broken away.

Fig. 4 is a detail cross section on the line 4—4 of Fig. 1.

Referring to the drawings by numerals 50 of reference:—

The machine proper is supported in a suitable frame work and casing indicated generally at 1 which may be cast in one piece and mounted on rollers 2. The open 55 front of the casing is closed by a door 3 which swings on hinges 4 while the frame

work at the front is joined by the transverse tie pieces 5. A hanger 6 depends from the cross piece 5 and aligns with a similar hanger, not shown, which depends from a 60 transverse tie piece formed integral with the rear frame work. A horizontally disposed shaft 7 is journaled in these hangers and on this shaft is mounted a worm wheel 8 and a worm 9. The worm wheel 8 is 65 driven by a worm 10 formed on the horizontally disposed shaft 11 of a motor 12. The motor 12 is suitably supported in the frame work 1 and the end of its shaft 11 is journaled in a standard 13 which is secured 70 within the frame work 1.

A horizontally disposed shaft 14 extends transversely of the machine and is journaled in the side frame work, and on this shaft is loosely mounted a worm wheel 15. Worm 75 wheel 15 is formed with one member of a clutch the other member 16 of which is feathered on the shaft and is thrown by a lever 17 to put the mechanism in and out of gear. A mutilated spur gear 18, adapted 80 to mesh with a pinion 18', is mounted substantially at the center of the shaft 14, and on each end of the shaft 14 is secured a wrist plate 19. An adjustable wrist pin, formed with a hand grip end 20, is mounted 85 on each wrist plate and slides thereon in a guideway 21 and is clamped in place when adjusted by a clamping nut operated through the hand lever 22. A scale 23 may be provided along the guideway, and a 90 pointer 24, movable with the wrist pin will indicate the amount of liquid which the machine is set to deliver. A pitman 25 is pivotally secured to each wrist pin from which it rises, and the pitman is formed with an 95 attenuated upper end 26 which passes through the bore formed in a block 27. The block 27 rocks on its trunnions 28 which are journaled in a retaining yoke 29 and a sliding block 30 to which the retaining yoke is 100 secured by tap screws or otherwise.

A coiled spring 25' surrounds the attenuated end 26 and is confined between a knob 26', secured to the free end of the pitman, and the retaining yoke 29.

Each sliding block 30 is formed with beveled longitudinal edges which slide in grooves formed in the arms of a U-shaped guide plate 31. The guide plates 31 are bolted or otherwise secured at each side of 110 the casing 1. Each sliding block is formed with an inwardly and upwardly extending

arm 32, the horizontally disposed upper end of which is secured by bolts 33 or otherwise, to a horizontally disposed plate 34. Valves 35, each provided with a stem 36, depend from the plate 34 to which the upper end of each stem is secured by nuts 37 which are threaded on the stem below and above the plate. The valve stems 36 pass through openings formed in the cover 38 of a tank 39 and secured to the cover about each opening is a stuffing box 40 through which the valve stem reciprocates.

A horizontally disposed plate 41 formed with depending edges 42, is supported within the casing 1, by brackets 43, which are secured to the casing 1. The plate 41 is provided with a series of openings 44. The tank 39 is seated on the plate 41, and the bottom of the tank is formed with a series 20 of downwardly projecting circular bosses 45, each provided with a central circular aperture. The walls of the apertures are stepped as shown and within each opening is seated a ring 46 which is centrally apertured to form a seat for the valve 35. A liquid supply pipe 47 and an air supply pipe 48 rise from suitable points on the cover of the tank 39.

Extending longitudinally of the casing 1, 30 and below the plate 41 is a track formed of longitudinally disposed rails 49, which are secured to and supported on the frame work 1. A platform truck 50, mounted on flanged wheels 51 is adapted to the track and each truck has a rack 52 secured to its under surface and extending longitudinally thereof. The rack 52 is positioned to be engaged by the teeth of the pinion 18'. A series of cans 53 are placed on the truck in 35 position to be drawn beneath the ports of the tank 39 and receive liquid therefrom. Bracket arms 54 may be secured to the frame work 1 at the front and rear of the machine to support the outwardly projecting end of the track.

A transfer system may be provided for consisting of a supporting frame 55 upon which the rails 56 are secured. A truck 57, formed with rails 58 which align with the 50 rails 49 is mounted on flanged wheels 59 which are adapted to engage the rails 56. This truck receives the truck from the machine, loaded with filled cans, and may then be propelled along the rails 56 to one side of the machine. At the end of the rails 56 and their supporting frame 55, and extending at right angles thereto, is another supporting frame 60 upon which rails, adapted to align with the rails 58 on truck 57, are secured, 55 and these rails are preferably positioned parallel to the rails 49. Another supporting frame 61 extends from the rear of the machine to the frame 60 and parallel to the frame 55. This frame has rails 62 secured thereon and is provided with a truck in all 60

respects similar to the truck 57 just described.

In practice the device operates as follows:—Paint or other liquid is caused to flow into the tank 39 through the supply pipe 47, air at the same time being expelled from the tank through the pipe 48. Trucks are loaded with receptacles and brought into position, as indicated in Fig. 2, and coupled together. The wrist pin is set with the pointer 24 at the point on the scale corresponding to the capacity of the receptacle. The motor 12 is started and the clutch thrown in. As viewed in Fig. 2, the milled gear 18 will turn contra clockwise 70 while the pinion 18' will turn clockwise. This will draw a truck with its receptacles into position to be filled. While the milled gear is in mesh with the pinion and drawing a truck into position, the spring 25 is being compressed and the valves 35 will be held upon their seats. When the gears 18 and 18' are disengaged the pitman has started to rise and its enlarged portion contacts the block 27 and yoke 29 and raises 75 the sliding block. This causes the plate 34 to be carried upward, and draws the valves 35 from their seats and allows liquid to flow from the tank to the underlying receptacles. When the cans are full the valves are again 80 closed by the descending pitman and the gears 18 and 18' again come into engagement to expel the loaded truck from the machine and draw another truck into position.

When the loaded truck is forced outwardly from the machine, it is uncoupled and run onto the truck 57. The truck 57 is then propelled along the rails 56 to their end, where the loaded truck may be run off 100 the truck 57 onto the rails on frame 60 and the truck 57 returned to its starting point. The loaded truck is now emptied of its full receptacles and propelled to the end of supporting frame 60 where it will run on the 105 truck on rails 62. Here empty receptacles can be loaded on the truck and brought to position to enter the machine.

As will be readily apparent the valves and their seats can be easily removed for cleaning whenever it becomes necessary.

Having described my invention, what I claim as new and desire to secure by Letters-Patent, is:—

1. A receptacle filling machine, including 120 a frame, a liquid containing tank supported in the frame and provided with discharge ports, receptacle supports, means for moving the supports through the frame to bring receptacles successively below the ports, 125 means for delivering a predetermined bulk to the receptacle upon the support, said means including a shaft, wrist plates on the shaft, wrist pins adjustable on the plates, a pitman pivoted to each wrist pin, 130

a sliding block actuated by each pitman, a plate carried by the sliding blocks, valves depending from the plate and adapted to normally close the discharge ports, and 5 means for rotating the shaft.

2. A receptacle filling machine, including a frame, a liquid containing tank supported in the frame, and provided with discharge ports, receptacle supports, means for moving the supports through the frame to bring the receptacles successively below the ports, means for delivering a predetermined bulk to the receptacle upon the support, said means including a shaft, pitmen attached to 10 the shaft, blocks slidable on the frame and having apertures, the free ends of the pit-

men slidable through the apertures, shoulders on the pitmen and seatable upwardly against the blocks to lift the blocks, yielding connections between the blocks and the 20 pitmen for forcing the blocks downwardly, a plate carried by the blocks, and valves carried by the plate for closing the discharge ports.

In testimony that I claim the foregoing 25 as my own, I have hereto affixed my signature in the presence of two witnesses.

ELMER L. POWL.
